ABSTRACT: This invention relates to an automatic ball-teeing unit featuring a servosystem in combination with a base means and a ball-elevating means. Said servosystem provides a novel means of controlling said ball-elevating means. The unit can be preprogrammed to offer unlimited flexibility as to tee height positioning. The invention utilizes error detector means to measure the difference in signal between a position sensor and command transducers, to provide an error-actuating signal. Said error signal is an indication of the lack of correspondence between the input and output of the servosystem. This lack of correspondence will start the prime mover into action to reduce or eradicate the error, thus elevating the ball-elevating means to a preset position. Due to utilization of said servosystem, said ball-elevating means can be programmed to provide a lowered ball-receiving position, an elevated ball-striking position and any preset intermediate ball-striking position automatically.

AUTOMATIC GOLF BALL TEEING MEANS

The said invention is particularly adaptable for use in both indoor and outdoor golf ranges, and in automatic installations of the type revealed in my copending patent applications Ser. No. 480,713 filed Aug. 18, 1965, Ser. No. 610,556 filed Jan. 20, 1967, and Ser. No. 610,557 filed Jan. 20, 1967.

Accordingly, objects of this invention are as follows:

To provide a ball-teeing means that is structurally simple and low in cost of both manufacture and maintenance.

To provide an automatic ball-teeing means possessing the reliability demanded by completely automated-type golf ranges.

To provide a ball-teeing means possessing two ball-striking positions, automatically and alternately selective.

To provide an automatic ball-teeing means that will relieve the golfer of the duty of teeing balls manually.

To provide a ball-teeing means that can be utilized in both completely automated and nonautomated-type golf ranges.

To provide a ball-teeing means operable via servocontrol.

These objects and other objects of this invention should be discerned and appreciated from the description and claims taken in conjunction with the accompanying drawings, in which:

FIG. 1 is a schematic side elevation view of the first embodiment of the invention.

FIG. 2 is a schematic side elevation view of the second embodiment of the invention.

FIG. 3 is a schematic side elevation view of the third embodiment of the invention.

FIG. 4 is a block diagram of the servosystem employed in the invention.

To utilize the disclosed embodiments of this invention, it is essential that the said embodiments be fixedly mounted with respect to floor A and operatively linked with a ball-delivery means C which provides balls B singly upon demand.

The invention consists essentially of a base means, a ball-elevating means, and a servosystem to effectuate three-position action to the said ball-elevating means.

The first embodiment shown in FIG. 1 consists basically of a base means having cup 1 and a mounting plate 2; a ball-elevating means 4, such as a spring reinforced flexible plastic hose; a switching sensor 11; a position sensor 12; and a prime mover 8, such as a fluid cylinder functionally associated as part of the servosystem to effectuate said three-position action.

The second embodiment shown in FIG. 2 consists basically of a base means having a cup 24 and a mounting plate 25; a ball-elevating means 27, such as a close-wound helical spring; a switching sensor 30; a position sensor 34; and a prime mover 35, such as a servogearmotor drives a flexible connector arrangement possessing sprockets and chain functional as the followup mechanism of the servosystem.

The third embodiment shown in FIG. 3 consists basically of a base means having a cup 37 and a mounting plate 38; a ball-elevating means 40, such as a flexible tube; a switching sensor 42; a position sensor 45; and a prime mover 46, such as a servogearmotor which drives a rack and gear arrangement functional as the followup mechanism of the servosystem.

Terms herein utilized should bear interpretation as follows:

Base means includes the cup with an aperture at the side for attachment of the ball-delivery means, an opening in the bottom for journaling of the ball-elevating means, and a mounting plate for the mounting of the prime mover with followup mechanism and required ancillary elements.

Ball-elevating means encompasses such commercially available items as close-wound helical spring, spring reinforced flexible plastic hose, flexible plastic or rubber tube, plastic-coated rubber tube, etc.

Servosystem is defined as a combination of elements for the control of a source of power in which the output of the system, or some function thereof, is fed back for comparison with the input and the difference between these quantities is used in controlling the power. The servosystem also includes a followup mechanism in conjunction with the basic components indicated by the block diagram of FIG. 4.

Prime movers encompass such elements as servogearmotors, lineal or rotary fluid actuators, etc.

Command transducers are utilized to provide the desired reference input and can exist as potentiometers, linear-variable differential transformers, microsynchros, synchros, E-transformers, etc.

Switching sensors encompass such elements as photosensors, acoustic sensors, etc.

Position sensors are utilized to transform a displacement into an electrical signal that is the measure of the said displacement. Potentiometers, linear-variable differential transformers, microsynchros, synchros, E-transformers, etc. can be utilized to perform the indicated function.

The error detector consists of a position sensor and command transducers arranged into a computing-type circuit, thus functional in measuring the difference between the command and controlled variable, and in turn providing an actuating error signal. This actuating error signal exists as an electrical signal whose magnitude and polarity indicates the lack of correspondence between the said command and controlled variables.

Controller 14 is a device driven by a signal from the switching sensor and functional in amplifying the said signal, if required, to the magnitude necessary to actuate a control relay.

Controller 23 is a device driven by the actuating error signal and functional in amplifying the said error signal and providing it in proper form and magnitude to control the prime mover.

Followup mechanisms encompass such devices as flexible connectors, rack and gear drives, linkages, etc.

Flexible connectors appear in such forms as belts, cables, and chains associated with pulleys, sheaves, and sprockets respectively.

A fluid is construed to include both gaseous and liquid media.

In explaining the invention in detail it can be discerned that this invention is capable of many embodiments of which three are illustrated in the accompanying drawings and also herein described.

The first embodiment consists of a base means defined by cup 1 to which a mounting plate 2 is fixedly secured as shown in FIG. 1. Said cup 1 has a ball inlet aperture 3 located within its cylindrical sidewall for mounting of ball-delivery means C in depending relation therefrom, and in registry with said aperture 3; an opening within the bottom for the journaling of ball-elevating means 4, such as a spring reinforced flexible hose; and an opening 5 at the top to provide for ball exit when placed in registry with opening in floor A.

Ball elevating means 4 is reciprocably mounted within bottom opening of said cup 1 with its lower end fixedly mounted to carrier 6, which in turn is fixedly mounted to end of rod 7 as shown. Said rod 7 is slidably mounted with respect to the prime mover 8, such as a fluid cylinder, which is fixedly mounted to said mounting plate 2. Said prime mover 8 has port 9 located at the rod end and port 10 located at the blind end for connection to external fluid control means such as a servovalve.

Fixedly mounted to carrier 6 and depending within central opening of ball-elevating means 4, is switching sensor 11 such as a photoelectric sensor. Leads of said switching sensor are disposed downwardly through and emerging from said carrier 6 thus providing accessibility for connection to electrical control means.

Position sensor 12 such as a linear motion potentiometer is fixedly mounted to mounting plate 2 with connective end of shaft 13 fixedly mounted to carrier 6 and the other end reciprocably mounted within the sensor. Said sensor 12, prime mover 8, and ball-elevating means 4 are all disposed with their translating longitudinal axes substantially parallel to each other as shown.

FIG. 4 shows a block diagram of the servosystem employed in the invention, having the prime mover 8, position sensor 12, and switching sensor 11 fixedly mounted to associated ele-

ments as shown in FIG. 1. The remaining elements depicted in the said block diagram are contained in a remotely located system control package.

Ball B, upon conveyance through the ball-delivery means C and through ball inlet aperture 3, will enter cup 1 and gravitate upon the tee portion of ball-elevating means 4 as shown in FIG. 1. In so doing, the switching sensor 11 will effectuate a signal to associated controller 14. Said controller will function to close contacts 15 and open contacts 16, thus conveying the said electrical signal to the upper position command transducer 19 through closed contacts 17. Contacts 17 and 18 are functionally associated with a control relay whose action can be initiated either manually or automatically to provide for the selection of either the upper or the intermediate ball-striking tee position.

Upper position command transducer 19 such as a potentiometer is preset to provide a command reference signal r , of such magnitude, as to be representative of the ball-elevating means at its desired uppermost ball-striking position. This reference signal r is fed to the error detector 22 and compared to the electrical feedback signal b emitted from the position sensor 12 as the existing position indication of the ball-elevating means. The difference between the said signals constitutes the actuating error signal e which is fed to the controller 23. Said controller consists basically of an amplifier and a servovalve which supplies controlled fluid power to the prime mover 8. The said amplifier is functional in providing the electrical signal to the servovalve to cause operation thereof. Said operation of the said servovalve from null position will cause fluid to flow to port 9 of prime mover 8. This will cause rod 7 to retract within said prime mover 8, and in so doing, carrier 6 will cause shaft 13 of position sensor 12 such as a potentiometer to be displaced. Also, the ball-elevating means 4 will elevate until the ball B emerges through opening 5 to the required uppermost height with respect to floor A, for golfer usage. The resulting motion of the prime mover 8 will cause the position sensor's feedback signal b to become equal to the command reference signal r , provided by the preset upper position command transducer 19, so that the actuating error signal e is reduced to zero, thereby, nulling the servovalve to cut off fluid flow to port 9. With the termination of flow to port 9, the ball-elevating means 4 will stop and maintain this desired uppermost position.

When ball B is dislodged from the tee portion of the ball-elevating means 4, the switching sensor 11 will again effectuate a signal to controller 14 to cause contacts 15 to open and contacts 16 to close. This will provide an electrical signal to the lower position command transducer 21 such as a potentiometer which is preset to establish a command reference signal r of such magnitude as to be representative of the said ball-elevating means at its desired lowermost ball-receiving position. This reference signal r is fed to the error detector 22 and compared to the electrical feedback signal b emitted from the position sensor 12. The difference between the two said signals constitutes the new actuating error signal e which is fed to controller 23 to cause operation of the functionally associated servovalve. Now, operation of the said servovalve from null will cause fluid to exhaust from port 9 and simultaneously direct flow into port 10 of the said prime mover 8 to extend rod 7. In so doing, carrier 6 will cause shaft 13 of the position sensor 12 to be again displaced and ball-elevating means 4 to descend toward the desired lowermost ball-receiving position. The resulting prime mover displacement will cause the position sensor's feedback signal b to become equal to the command reference signal r provided by the lower position command transducer 21, so that the actuating error signal e is again reduced to zero, thereby, nulling the servovalve to cut off fluid flow to port 10. With the termination of flow to port 10, the ball-elevating means 4 will stop and maintain this desired lowermost ball-receiving position until another ball B is fed onto its tee portion to initiate another ball-teeing cycle.

When required to utilize iron golf clubs in hitting balls from the tee, the ball-elevating means will elevate to the intermediate ball-striking position. To promote this function, contacts 17 are opened and contacts 18 are closed by way of relay action. This renders the upper position command transducer 19 inoperative and the intermediate position command transducer 20 such as a potentiometer operative along with the lower position command transducer 21, thus making possible the operation of the ball-elevating means between the lowermost ball-receiving and the intermediate ball-striking positions.

10 The description of the sequence of operation between the said intermediate ball-striking and the lowermost ball-receiving positions is similar to that described in conjunction with the operation between the uppermost ball-striking and the lowermost ball-receiving positions. The only exception is that the command reference signal r , to elevate the ball-elevating means 4, is provided by the intermediate position command transducer 20 instead of the previously used upper position command transducer 19.

15 The second embodiment consists of a base means defined by cup 24 to which a mounting plate 25 is fixedly secured as shown in FIG. 2. Said cup 24 has a ball inlet aperture 26 located within its cylindrical sidewall for mounting of ball-delivery means C in depending relation, therefrom, and in registry with said aperture 26; an opening within the bottom for the journaling of ball-elevating means 27, such as a close-wound helical spring; and an opening 28 at the top to provide for ball exit when placed in registry with opening in floor A.

20 Ball-elevating means 27 is reciprocably mounted within bottom opening of said cup 24 with its lower end fixedly mounted to carrier 29 which in turn is fixedly mounted to chain 33 as shown. Fixedly mounted to carrier 29 and depending within central opening of ball-elevating means 27, is switching sensor 30 such as a photoelectric sensor. Leads of said sensor 30 25 emerge from bottom of said carrier 29 for connection to electrical control means.

25 Prime mover 35, such as a servogearmotor, is fixedly mounted to the backside of mounting plate 25 with its rotatable shaft (not shown) protruding through said mounting plate. 30 Fixedly mounted on said rotatable shaft is drive sprocket 32. Also, centrally and fixedly mounted within end of said prime mover shaft is the rotatably shaft (not shown) of position sensor 34 such as a potentiometer whose housing is in turn fixedly mounted with respect to mounting plate 25. Sprocket 31 is 35 rotatably mounted to shaft 36 which is fixedly mounted to mounting plate 25 by conventional means. Chain 33 is drivably placed around displaced sprockets 31 and 32 in closed-loop fashion as shown. The distance between said 40 sprockets must be such as to effectuate proper displacement of ball-elevating means 27 between its lowermost ball-receiving and its uppermost ball-striking position. Flexible connector arrangement, consisting of carrier 29, chain 33, and sprockets 31 and 32, is operative as the servosystem's 45 followup mechanism.

50 FIG. 4 shows the block diagram of the servosystem employed in connection with this embodiment, having prime mover 35, position sensor 34, and switching sensor 30 fixedly mounted to associated elements as shown in FIG. 2. The remaining elements depicted in the said block diagram are 55 contained in a discrete system control package.

55 The third embodiment consists of a base means defined by cup 37 to which a mounting plate 38 is fixedly secured as shown in FIG. 3. Said cup 37 has a ball inlet aperture 39 located within its cylindrical sidewall for mounting of ball-delivery means C in depending relation, therefrom, and in registry with said aperture 39; an opening within the bottom for the journaling of both the ball-elevating means 40, such as a flexible tube, and a tubular rack 43; and an opening 41 at the 60 top to provide for ball exit when placed in registry with opening in floor A.

65 Ball-elevating means 40 is reciprocably mounted with respect to bottom opening of said cup 37, having its lower end fixedly mounted to top of tubular rack 43 as shown. Centrally and fixedly mounted to top of reciprocably mounted rack 43 70

75

and depending within central opening of said ball-elevating means 40, is switching sensor 42. Leads of said sensor 42 such as a photoelectric sensor are disposed downwardly through and emerging from the bottom of said rack 43, thus providing accessibility for connection to electrical control means.

Prime mover 46, such as a servogearmotor, is fixedly mounted to the back side of mounting plate 38 with its rotatable shaft (not shown) protruding through said mounting plate. Fixedly mounted on said rotatable shaft is drive gear 44, which in turn is drivably engaged with said rack 43. Also, centrally and fixedly mounted within end of said prime mover shaft is the rotatable shaft (not shown) of position sensor 45 such as a potentiometer whose housing is in turn fixedly mounted with respect to mounting plate 38. Drive combination of rack 43 and gear 44, is operative as the servosystem's followup mechanism.

FIG. 4 shows the block diagram of the servosystem employed in connection with this embodiment, having prime mover 46, position sensor 45, and switching sensor 42 fixedly mounted to associated elements as shown in FIG. 3. The remaining elements depicted in the said block diagram are contained as a discrete system control package.

Due to the close similarity between the second and third embodiments, operation will be described to encompass and apply to both embodiments in order to evade repetitious disclosure.

Ball B, upon conveyance through the ball-delivery means C and through ball inlet aperture, will enter the cup and gravitate upon the tee portion of ball-elevating means as shown in FIGS. 2 and 3. In so doing, the switching sensor will effectuate a signal to associated controller 14. Said controller will function to close contacts 15 and open contacts 16, thus conveying said electrical signal to the upper position command transducer 19 through closed contacts 17.

Upper position command transducer 19 is preset to provide a command reference signal r of such magnitude as to be representative of the ball-elevating means at its desired uppermost ball-striking position. This reference signal r is fed to the error detector 22 and compared to the electrical feedback signal b emitted from the position sensor as the existing position indication of the ball-elevating means. The difference between the said signals constitutes the actuating error signal e fed to the controller 47 such as an amplifier which in turn supplies controlled electrical power to the prime mover. Operation of the said controller 47 will cause the shaft of the prime mover to rotate in such a manner as to drive the ball-elevating means upwardly via the said followup mechanism. Rotation of the prime mover shaft will also cause the position sensor's shaft to be displaced until the said ball-elevating means with ball B emerges through opening of floor A to the preselected and desired uppermost height. At this uppermost height, the position sensor's feedback signal b will equal the command reference signal r provided by the preset upper position command transducer 19, thus reducing the actuating error signal e to zero and stopping the prime mover.

When the ball B is dislodged from the tee portion of the ball-elevating means, the switching sensor will again effectuate a signal to controller 14 to cause contacts 15 to open and contacts 16 to close. This will provide an electrical signal to the lower position command transducer 21 which is preset to establish a command reference signal r of such magnitude as to be representative of the said ball-elevating means at its desired lowermost ball-receiving position. Reference signal r is then fed to the error detector 22 and compared to the electrical feedback signal b emitted from the position sensor. The difference between the two said signals constitutes the new actuating error signal e fed to controller 47 which in turn supplies controlled electrical power to the prime mover. Operation of the said controller 47 will cause the shaft of said prime mover to rotate in such a manner as to drive the ball-elevating means downwardly via the said followup mechanism. Rotation of the prime mover shaft will cause the position sensor's shaft

to be displaced until the ball-elevating means is lowered to its lowermost ball-receiving position. At this position, the position sensor's feedback signal b will equal the command reference signal r provided by the preset lower position command transducer 21, thus reducing the actuating error signal e to zero and maintaining the said ball-elevating means at this lowermost position until another ball B is fed onto its tee portion to initiate another ball-teeing cycle. Therefore, it can be discerned that if any signal exists at the input to the controller 23, the prime mover will rotate until that signal is reduced to zero.

When the intermediate ball-elevating means position is desired, contacts 17 are opened and contacts 18 are closed by relay action. This renders the upper position command transducer 19 inoperative and the intermediate position command transducer 20 operative along with the lower position command transducer 21, thus making possible the operation of the ball-elevating means between the lowermost ball-receiving and the intermediate ball-striking position.

The description of the sequence of operation, between the said intermediate ball-striking and the lowermost ball-receiving positions, is similar to that described in conjunction with the operation between the uppermost ball-striking and the lowermost ball-receiving positions. The only exception is that the command reference signal r , to elevate the ball-elevating means, is provided by the intermediate position command transducer 20 instead of the previously used upper position command transducer 19.

I claim:

- 30 1. An automatic ball-teeing apparatus with provisions for accommodating a ball-delivery means, comprising in combination, a base means; a ball-elevator means disposed with respect to said base means; and a servosystem operatively associated with said ball-elevator means to effectuate reciprocating movement thereto between a plurality of positions, said servosystem including a sensor means for providing a signal which is dependent on the position of the ball-elevator means, an input command transducer means for providing a signal dictating a preselected position to be assumed by said ball-elevator means, and error detector means for measuring the difference in the signals provided by said sensor means and said transducer means to effectuate an output signal dependent on said difference to drive the servosystem until the ball-elevator means moves to the preselected position.
- 45 2. The invention as defined in claim 1, wherein said ball-elevating means is a spring reinforced flexible plastic hose.
3. The invention as defined in claim 2, wherein said servosystem includes a fluid actuator as the prime mover.
4. The invention as defined in claim 3, wherein said transducer means includes a photoelectric switching sensor operative as a ball detection means.
- 50 5. The invention as defined in claim 1, wherein said ball-elevator means is a close-wound helical spring.
6. The invention as defined in claim 5, wherein said servosystem includes a flexible connector-type of followup mechanism to reciprocate the ball-elevator means.
7. The invention as defined in claim 6, wherein said servosystem includes a servogearmotor as the prime mover.
8. The invention as defined in claim 7, wherein said transducer means includes a photoelectric switching sensor operative as the ball detection means.
- 60 9. The invention as defined in claim 1, wherein said ball-elevator means is a flexible tube.
10. The invention as defined in claim 9, wherein said servosystem includes a rack and gear-type of followup mechanism to reciprocate the ball-elevator means.
11. The invention as defined in claim 10, wherein said servosystem includes a servogearmotor as the prime mover.
12. The invention as defined in claim 11, wherein said transducer means includes a photoelectric switching sensor operative as the ball detection means.
